(57) CLAIM

The ornamental design for an applicator for lip gloss, as shown and described.

DESCRIPTION

FIG. 1 is a perspective view of an applicator for lip gloss showing my new design;

FIG. 2 is a front view thereof, a rear view being identical to the front view thereof;

FIG. 3 is a plan view thereof;

FIG. 4 is a bottom view thereof; and,

FIG. 5 is a right side view thereof, a left side view being identical to the right side view thereof.

The broken lines depict portions of the applicator for lip gloss that form no part of claimed design.
